LINE SELECTOR SWITCH

Gerald Deakin, New York, N. Y., assignor to
 International Standard Electric Corporation,
 New York, N. Y., a corporation of Delaware

Application February 5, 1942, Serial No. 429,654

8 Claims. (Cl. 179—27.51)

This invention relates to new and useful improvements in telephone communication exchange systems and more particularly to equipment for finding a marked line, trunk, link or the like, as well as to a novel type of electro-mechanical switching device particularly suitable for use as a line finder, link finder, or trunk finder in such systems.

In accordance with the present invention the line, link or trunk which is marked by application of a distinctive potential to a conductor associated therewith, is found or identified by means of a very sensitive test device, such as a vacuum-tube test device, which requires extremely small currents for its response, and the apparatus for associating such highly sensitive test device with the marked conductors consists of a constantly rotating multi-contact hunting switch, hereinafter referred to as a detector switch, of somewhat unusual design.

More particularly, the detector switch which associates the vacuum tube test means with the marked conductors comprises a large number of stationary terminals, e. g., 25 to 200 terminals, a rotary wiper arranged to wipe over said terminals with a very light contact pressure, and means for maintaining the cooperative, coacting wiping surfaces of the stationary terminals and the moving wipers constantly covered with a film of oil.

It is true that switches operating in oil are known but so far as I am aware such switches have always been arranged to operate with comparatively high pressures in order that the film of oil between the coacting contact members may be broken down to provide a satisfactory electrical contact. Furthermore, it is usual to employ, for at least one of the coacting members, a carbon or graphite body or brush since contacts between two metallic members bathed in oil are generally assumed to be unsatisfactory. Moreover, so far as I am aware it has never been proposed to construct a detector type switch (i. e., a constantly rotating hunting switch having a large number of contacts) with lubricating means for flooding or bathing the cooperating contact surfaces in oil.

In spite of the generally accepted belief that satisfactory contacts for low voltages (i. e., voltages below 125 volts) cannot be made between metallic members copiously bathed in oil, at least without the use of very substantial contact pressures, and in spite of the fact that such oil switches as have been manufactured have always been designed with large contact pressures and have been employed for use with high voltages of

5 the order of several hundred volts or more, I have found that very reliable and satisfactory results may be obtained when a constantly rotating detector switch whose contacts are bathed in oil and have low contact pressures, is employed to connect the marked conductors to a sensitive test device responsive to small currents. This is somewhat surprising since it has generally been assumed that an attempt to make contact between members bathed in oil would provide not merely a high resistance connection but rather a substantially open connection so long as the mechanical contact pressure was comparatively low and the applied voltage was insufficient to cause disruptive breakdown of the oil film. Perhaps the fact is that even with a light contact pressure of the order of 10 grams per square millimeter or less, the oil film is always ruptured at some point between the cooperative wiping surfaces due to 10 minute roughnesses or irregularity thereof.

15 In any case whatever the explanation might be, I have found that a detector switch (i. e., a constantly rotating hunting type switch arranged to search successively over 20 or more stationary contacts at a rate of the order of 15-300 contacts per second) may be successfully used to interconnect a thermionic testing mechanism with a marked conductor even when the potential used for marking the conductor is only of the order of 20 25 48 or 24 volts in magnitude and even when the contact pressures are as low as 20 grams and the contacts are quite smooth, well worn and have an area of about 4 square millimeters.

30 Preferably, the testing device should be a thermionic apparatus adjusted to respond to very small currents of the order of 80-800 microamperes or even less, and the rate of rotation of the detector switch should be low enough so that this does not wipe over its contacts at a rate of 35 more than 500 contacts per second. With such contact pressures and scanning rates I have found that very reliable operation may be secured even with marking voltages of 24 volts or even 12 volts.

40 Accordingly one feature of the present invention is the combination of a detector switch employing low contact pressure and a high contacting rate and having its contact surfaces copiously bathed in oil, with a highly sensitive test device, preferably of thermionic type and adapted to respond to currents of the order of 1 milliampere or less.

45 Another feature of the present invention is the provision of a novel switch structure par-

ticularly adapted for use as a detector switch in such combination.

The invention will be explained in detail as applied to a preferred embodiment illustrated in the drawings in which

Fig. 1 is a front elevation of a novel switch in accordance with my invention;

Fig. 2 is a vertical cross-section substantially along the lines 2—2 of Fig. 1, certain parts being shown in elevation;

Fig. 3 is a schematic circuit diagram of a portion of a telephone exchange embodying my invention.

Referring more particularly to Figs. 1 and 2, 1 is a cylindrical casing closed at one end and molded of insulating material with a row of terminals 2 projecting through the side wall. In the structure illustrated, the casing has a diameter of approximately 7 inches and carries 100 terminals. The outside ends of the terminals 2 are accessible for connection and the inside ends protrude far enough from the insulation to be engaged by wipers 3 and 4. Adjacent the terminals 2, feeder strips 5 and 6 run around the inside wall of cylinder 1, with connecting terminals 5a and 6a projecting to the outside. Strip 5 extends over approximately one-half and strip 6 over the second half of cylinder 1 and they are engaged by the wipers 3a and 4a as they wipe over the terminals 2.

The open end of the cylindrical casing is closed by a cover 7, the closure being made oil-tight by means of a gasket 8. The top 7 is held in place by screws 9.

A housing 10 is fastened to the outside of the cover 7. A ball-bearing 11 is mounted in one side of the housing 10 and in alignment therewith a ball-bearing 12 is mounted in the cover 7. A shaft 13 with one end seated in bearing 11 projects through bearing 12 in the cylinder 1. An arm 14 is fastened at its midpoint to the shaft 13 within casing 1. The wipers 3 and 4 are supported on the ends of the arm 14 by means of coiled springs 15, which press the wipers against the inside of the surface of the cylinder 1 and thus into engagement with the feeder strips 5 and 6 and terminals 2 on which they may happen to rest. I have found that if the surface with which wipers 3 and 4 cooperate is properly lubricated then the contact pressure may be as low as 20 grams although the wipers perform four complete revolutions per second.

The cylinder 1 has a cup-shaped extension or well 16 communicating with the interior of the cylinder. The well 16 is filled with lubricating oil as is the inside of the cylinder up to a point indicated by the dotted line 17, so that during each revolution the wipers 3 and 4 can dip into the pool of oil. An oil gauge 18 communicates with the well 16 to indicate the level of oil in the cylinder. Additional oil may be introduced by removing cap 19 and the oil may be drained out of the cylinder by removing screw-cap 20.

The shaft 13 is driven by means of a gear 21 mounted thereon intermediate the bearings 11, 12. The gear 21 is engaged by a worm 22 mounted on a driving shaft 23 intermediate two ball-bearings 24, 25, which are held in the housing 10 by means of side plates 27, 28. The shaft 23 projects through the side plate 28 and may be driven from any suitable source. The chamber 26 enclosed by the housing 10 and plates 27, 28 is filled with lubricating oil which may be introduced by removing screw 30 and drained

out by removing screw 31. Thus, the driving gear will constantly run in oil.

Referring to Fig. 3 which represents so much of an exchange system as is necessary for understanding the invention, H, H represent the hook switches of a number of subscribers' telephone sets which are respectively connected to the several lines a—b. In the central exchange each of these lines a—b has connected to it a number of simple ohmic resistors J, K, L. The L resistor which may be of the order of 50,000 ohms is permanently connected to the b wire of each line and its free end is connected to the negative pole of the exchange battery whose positive terminal is grounded in conventional fashion. The K resistor associated with each line is preferably equal in resistance to the L resistor and is connected at its free end to a contact of detector switch D preferably through an individual line resistor J, the wiper of the detector switch D being connected to the highly sensitive start circuit S over wire k.

The two wires a, b of each line are further multiplied to the terminals of a number of line finders as indicated in the drawings, only two such line finders I and II being shown although it will be understood that ordinarily a larger number will be provided. These line finders are shown as linear motion switches for convenience of illustration, but are preferably single motion rotary switches of step by step or power driven type. The a and b wires are also multiplied to connector terminals (not shown) in similar fashion.

Within the exchange a third or c wire is also associated with each line as is usual in common battery exchanges and this third or c wire is likewise multiplied along with the a and b wires to the terminals of the line finders as shown (and also similarly to the terminals of connectors not shown), each c wire being also connected to the junction between the J and K resistors individual to the line under consideration.

For starting one or more free line finders to search for a calling line a common start circuit S is provided. This circuit S comprises a vacuum tube V whose anode current constantly energizes an associated relay X except when the grid of this tube V is driven negative by a potential applied to the control wire k. In the absence of any current received over control wire k the grid of tube V is normally maintained at ground potential, or any other desired reference potential, by high resistance grid leak G which is connected to ground as shown, or to a bias source of any desired potential. An auxiliary relay Y of slow release type is provided and connected as shown to be operated upon the release of relay X.

In addition to the common start circuit S a common test circuit T generally similar to S is provided. This circuit T comprises the vacuum tube V' whose anode current normally energizes relay X', and also comprises a leak G' and an auxiliary relay Y' controlled from relay X'. The grid of tube V' is connected to the test wire c' of the first free line finder such as line finder I, through a common allotting device N which may be a relay chain or selecting switch and which operates in a manner well known per se to connect three wires f, c' and g of the first idle line finder circuit to the corresponding three wires of the common test circuit as shown.

The manner of operation of the system shown

in Fig. 3 is as follows: Upon the raising of the receiver at the calling station (say the station of the second subscriber's line 1) the hook switch H is closed, thus applying negative potential from the grounded exchange battery over resistor L, the b wire of the line, hook switch H, the a wire of the line, resistor K, resistor J, start wire k², to the corresponding contact of the detector switch D. The next time the wiper of this detector switch makes contact with its corresponding contact, this negative potential is extended through the wiper of this switch D, thence over control wire k, back contact of relay Y to the grid of tube V in the common start circuit S. The resulting decrease of anode current releases relay X, thus energizing relay Y in an obvious manner. A back contact of relay Y disconnects the grid of V, thus reenergizing relay X, but relay Y remains energized for an interval due to its slow release characteristics. During this energization of relay Y start magnet P of line finder I closes an obvious circuit through switch magnet M (in series with its own interrupter contacts if the switch is of step by step type, or directly if it is of power driven type), thus causing wipers W of the line finder switch MW to hunt for the calling line. If desired relay P may be omitted from the line finder of Fig. 3. In such case magnet M and its interrupter if any will be directly connected in place of the relay P.

When the wipers W of the line finder switch MW arrive at the calling line, negative potential from the grounded exchange battery is applied to the grid of tube V' in common test circuit T (over resistor L, the b wire of the line, hook switch H, the a wire of the line, resistor K, the c wire of the line, corresponding wiper W of the switch MW, the c' wire of the line finder I, the common allotting device N to the grid of tube V'). The resulting reduction of anode current releases relay X' which causes energization of relay Y' in an obvious manner. The operation of relay Y' opens the circuit of relay P thus stopping switch magnet M in the line finder. Simultaneously the operation of relay Y' energizes relay R in the line finder which switches through the a and b wires to the two windings of balanced bridge relay Q and simultaneously places ground on the c' wire of the line finder, and on conductor n which extends to the common allotting device thus causing this allotter to disconnect the test circuit T from line finder I and to prepare to connect this test circuit with the next idle line finder in known manner. The grounding of the c' wire by relay R in the line finder effectively removes the negative potential from the grid of tube V' since the above traced circuit for applying such negative potential to this grid is now by-passed to ground between resistors J and K (over the c wire, corresponding wiper W of switch MW, the c' wire of the line finder I, to the make contact of relay R). As a result relay X' promptly reenergizes but relay Y' remains actuated for an interval due to its slow release characteristics. The allotter N should be arranged in known manner so as not to connect test circuit T to the next line finder until after relay Y' has released, although the disconnection of T from line finder I may occur immediately after grounding of wire n as above mentioned.

In the line finder I, which is now connected to the calling line, bridge relay Q energizes over the line loop in the usual fashion, thus holding relay R over an obvious locking circuit of the

latter. The subsequent operations of the equipment beyond the line finder take place in the usual manner preferably under control of bridge relay Q.

It will be noted that now the line is balanced since resistor K is now grounded over the c wire at the end remote from the a side of the line, whereas the equal resistor L which is connected to the b side of the line is connected to the grounded exchange battery, thus providing a balanced line. The resistors K and L are thus effectively in shunt with the windings of bridge relay Q, but since these resistors are many times larger than the impedance of the talking circuit the presence of these resistors introduces substantially no loss in the circuit. It will also be noted that no negative potential is now supplied to the start wire k² from the calling line above considered, because the intermediate point between the resistors K and J associated with this line is now grounded over the c wire as above traced. Upon release of relay Y, therefore, no negative potential will be applied through the detector switch D to the grid of tube V of the start circuit S until another line initiates a call.

It will also be noted that in case one of the lines shown is called the application of ground potential to the c wire of this line from the connector in the usual fashion will similarly serve to balance the line and at the same time to prevent this line from applying negative potential to the common start circuit S when its switch hook H is closed to answer the call.

With the type of circuit shown in Fig. 3 the duration of closure of each contact of switch D should be preferably 3 milliseconds or more although by connecting a condenser around resistor G this time may be somewhat shortened, especially if resistor G is substantially higher than the three resistors J, K and L and the subscriber's line in series. Resistors J and K may suitably be 5000 to 50,000 ohms apiece, while resistor J may be 1000-2000 ohms or may even be omitted.

45 The tubes V and V' may be grid controlled gas-filled discharge tubes of the trigger type instead of high vacuum tubes so as to remain conducting when once ignited. In such case a special battery with grounded negative may be used for feeding the L resistors and relays X and X' may be correspondingly modified to operate upon the initiation of a call. Or high vacuum tubes may be used with a self-locking circuit of known type to remain either conducting or non-conducting until reset. Any of these expedients will permit a very brief contacting time for the commutating device D, thus permitting a very rapid operation of this device while still insuring operation (or release) of relay X.

50 Although certain embodiments of the invention have been shown and described for purposes of illustration, it will be understood that modifications, adaptations and alterations thereof occurring to one skilled in the art may be made without departing from the scope of the invention as defined in the appended claims.

What I claim is:

1. In a telecommunication exchange system the combination of a hunting switch comprising a number of fixed contacts and a wiper wiping thereacross, means for applying low tension marking potential to one of said fixed contacts, means for maintaining the cooperating surfaces of said wiper and contacts continually wet with oil, and test means responsive to weak currents

connected to the wiper of said switch for responding to the presence of said marking potential on said one of said contacts.

2. In a telecommunication exchange system a terminal bank, a wiper engaging said terminal bank, means for continuously moving said wiper to cause it to wipe repeatedly over said bank, means including said wiper for continuously oiling said bank, means for applying low tension marking potential to a terminal of said bank, and test means responsive to weak currents connected to the wiper of said switch for responding to the presence of said marking potential on said terminal.

3. A telephone type hunting switch comprising a terminal bank, a wiper engaging said terminal bank, means for continuously moving said wiper to cause it to wipe repeatedly over the terminals of said bank, and an oil bath into which said wiper dips periodically during its motion.

4. In a telephone selector switch, a casing, a row of terminals in said casing, a cover for said casing, wipers cooperating with said terminals, a shaft for rotating said wipers, and lubricating oil in said casing into which the wipers dip during each revolution of the shaft.

5. In a telephone selector switch, a casing of insulating material, a row of terminals projecting through the side wall of the casing, a cover for said casing, wipers in said casing resiliently pressed against said terminals, a shaft for rotating said wipers projecting through said cover, lubricating oil in said casing into which the wipers dip during each revolution, a second casing mounted on said cover, bearings and a driving gear for said shaft within the second casing, and lubricating oil filling said second casing.

6. In a telephone selector switch, a cylindrical casing of insulating material, a row of terminals projecting through the side wall of the casing, a cover for said casing, an arm in said casing having wipers at its two ends spring-pressed into engagement with said terminals, a shaft for rotating said arm projecting through said cover, lubricating oil in said casing into which the wipers dip during each revolution of the arm, a second casing mounted on said cover, bearings and a driving gear for said shaft within the second casing, a driving shaft having bearings and a worm engaging said gear also mounted within said second casing, and lubricating oil filling said second casing.

7. In a telecommunication exchange system the combination of a constantly operating hunting switch comprising a number of fixed contacts and a wiper wiping thereacross with a pressure of less than 10 grams per square millimeter at a rate in excess of 10 contacts per second, means for applying low tension marking potential to one of said stationary contacts, means for continually bathing said contacts with oil, and electron discharge test means responsive to currents of less than one millampere connected to the wiper of said switch for responding to the presence of said marking potential on said one of said contacts.

8. In a telephone selector switch, a terminal bank including a wiper engaging said terminal bank, means for moving said wiper over the terminals of said bank, and an oil bath into which said wiper dips periodically during its motion.

GERALD DEAKIN.
